UNITED STATES PATENT OFFICE

2,423,856

AUTOMATIC GUN CONTROL FOR TANKS

Albert Rivington Stone, Belair, Md.

Application June 24, 1943, Serial No. 492,139

13 Claims. (Cl. 89—41)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to the positioning or training of guns carried by tanks and other vehicles, and more particularly to means for rotating the gun in response to the changes in directions of the tank.

Assume, for an example, a tank moving along a rectilinear east to west course with its gun trained on a target positioned directly north. As the tank progresses on its east to west course, the gunner keeping the target in sight will rotate the gun turret in a clockwise direction. This manual traversing rotation of the gun is required solely by the rectilinear travel of the tank, i. e., it is not occasioned by change in direction, since the tank course is assumed to be rectilinear. Suppose now that the tank changes its direction by veering to a west-south point of the compass, making a 45° angle to the original east-west path of the tank, i. e., in a counterclockwise sense. This change in direction of the tank requires a very considerable rotation of the gun turret in a clockwise sense. The purpose of this invention is to provide mechanical means which will automatically rotate the gun turret in this manner, to compensate for the change in direction of tank movement. Of course this automatic gun rotation will not maintain the gun trained on the target; the gunner will be required to additionally rotate the gun turret to keep the target in sight, the extent of such additional gun rotation will depend on the speed of the tank and other factors. The gun rotation imparted by the device of this invention will merely maintain the gun aimed in the general direction of the target. To explain, if the gun had been pointed north in the example above assumed, the device of this invention will maintain the gun pointing to the north. But the south-north line through the gun will have been moved or offset to the west, due to the movement of the tank in that general direction.

An embodiment of the automatic positioning or compensating device of this invention is shown in the accompanying drawings, wherein:

Fig. 1 is a plan view of the center and rear portion of a tank, showing the rear drive transmission and the gun turret, together with the compensating mechanism of this invention.

Fig. 2 is a plan view of a power-providing mechanism to supplement the "Selsyn" system employed between the tank drive and the gun turret.

2

Fig. 3 is a side elevation of the mechanism of Fig. 2.

Fig. 4 is a section on the line 4—4 of Fig. 3.

Fig. 5 is a detail of the solenoid drive employed in the mechanism of Figs. 2 to 4.

The center and rear portion of a tank designated 1 is shown in Fig. 1, with left and right wheels or track sprockets, respectively, 2 and 3. The two wheels are connected by flexible shaft cable 4 or the like to a differential, which will be designated as the "primary differential" to distinguish from other differentials subsequently described. The left wheel 2 is operatively connected to one of the bevel gears 12 of differential 10 while the right wheel is operatively connected to the other bevel gear 13. It should be noted that the bevel gear 4b at the wheel end of the flexible shaft connection to the left wheel meshes with the left wheel bevel 2a on the side thereof opposite to the side at which the bevel gear 4b at the wheel end of the right wheel meshes with the bevel 3a. Hence the two bevels of primary differential 10 will be rotated by their respective tank wheels in opposite directions. If the tank is traveling along a rectilinear path, the two bevels will be turning at the same rate but in opposite directions. Hence the output or spider member 11 of the primary differential will remain stationary, its planetary bevels turning idly.

30 The output shaft of the primary differential is connected to the transmitter 15 of a "Selsyn" transmission, the receiver, pick-off and follow-up unit 25 of which is positioned close to the gun turret represented in Fig. 1 by the large crown gear 6. The Selsyn receiver 25 is connected, through a power-providing means subsequently described, to one of the bevels 27 of a differential which will be referred to as the "balancing differential" for reasons soon apparent. The other bevel 17 of the balancing differential is connected by a shaft 7 and the gears shown to the said crown gear 6 of the gun turret. The output or spider member 28 of the balancing differential is connected to one bevel 38 of a third differential,

35 the other bevel 39 of which is turned by a hand-wheel 9. The output or spider member of the third differential is connected to an oilgear valve 18 which forms part of a hydraulic system which includes a hydraulic motor 8 geared to the crown gear 6 of the gun turret.

40 When the tank is caused to change its direction, the wheels 2 and 3 will turn at different speeds, thus causing a turning of the output member 11 of the differential which depends upon the difference in wheel speeds and hence the extent of

turning or change of direction of the vehicle. To reduce false effect upon the primary differential due to rapid slipping of one or both of the wheels or tracks, acceleration limit couplings 5 are inserted in the flexible shaft connection from the tank wheels to the primary differential; friction clutches in the acceleration limit couplings are caused to slip when the wheel shafts tend to accelerate above a predetermined limit. The precise degree of turning of the output shaft of the primary differential is transmitted by the "Selsyn" system 15-25 through the balancing differential to the combining differential which causes the oil-gear valve 18 to open thus causing hydraulic pressure, from an accumulator (not shown), to motivate motor 8 and rotate the gun turret in accordance with the extent of tank change of direction. As explained above, the gunner meanwhile would manually turn the gun turret as he endeavors to keep the target in sight; this he does by means of handwheel 9. It is thus seen that the output from the balancing differential and the manual turning of handwheel 9 are combined at this differential; the combined output of manual gun training and the automatic gun turning taking into account vehicle change of direction are thus transmitted to the oilgear valve 18.

The oilgear valve 18 would remain in open position, to the extent it has been opened by manual gear training and automatic gear turning, and thus continue to motivate motor 8, were it not for the presence of the balancing differential. The turning of the gun turret, combined manual and automatic operation, as described, causes, through its crown gear 6 and the shaft 7, rotation of bevel gear 17 of the balancing differential in a direction opposite to the rotation of bevel 27 and to an extent equal to the combined turning of the gun turret. This rotation of bevel 17 of the balancing differential is transmitted through the combining differential to the oilgear valve 18, thus moving it to closed position.

The "Selsyn" system, more particularly, its receiver or motor 25', is incapable of driving the heavy mechanism of the differentials and their connecting gears and the oilgear valve 18. The means now to be described are provided to furnish the necessary power to accomplish such driving under regulatory control of "Selsyn" motor 25'. Aligned with the shaft 24 of the "Selsyn" motor 25', Figs. 2 and 3, is a shaft 34 mounted in bearings as shown. One end of shaft 34 faces "Selsyn" motor shaft 24. At the other end of shaft 34 is secured the bevel 27 of the balancing differential. At the end of Selsyn motor shaft 24 is secured a lobed disc 26. A sleeve or bracket 37 has a bore smoothly fitting about shaft 34. This bracket has an arm 37' that is fixed by screws 46 to the standard or support 47 for the inner end of shaft 34. A post 35 is fixed to or formed integrally with, bracket 37. A contact blade 36 has one end fixed within a receiving aperture in the outer or distal end of post 35, as by means of a set screw 48. The blade 36 is of steel or other conducting material and possesses a resiliency that, in combination with its fixed end in post 35, acts to maintain said blade in centralized position between the vertical portions of an inverted V-shaped bracket 32. The other end of blade 36 carries a roller 33 of a size to be received between the lobes or serrations of disc 26, as clearly shown at Fig. 4. On the inner face of both vertical legs of the U-shaped bracket 32 is secured an electrical contact, the contact on the left leg, as viewed in Fig. 4, is designated 30, the right contact is designated 31. The left con-

tact 30 is wired to a solenoid 40, see Fig. 5, the other terminal of which is grounded; the right contact 31 is wired to a solenoid 41, also grounded as shown. The blade 36 is wired to a source of current as shown. The armatures of the solenoids 40 and 41 are implemented with pawls, respectively 42 and 43 which cooperate with ratchet wheels secured on shaft 34, respectively, 44 and 45. It will be observed, best from Fig. 5, that the pawls are disposed in a manner to turn shaft 34 in opposite directions.

It will be understood that the number of serrations or lobes on disc 26 is equal to the number of teeth on each of the ratchet wheels 44 and 45, and that the resiliency of blade 36 urges said blade to a centralized position in which it is out of engagement with contacts 30 and 31.

When the lobed disc 26 turns clockwise, as viewed in Fig. 4, the roller 33 will be moved to the right to cause circuit-closing contact between blade 36 and contact 31 each time a lobe of disc 26 passes. When movement of the disc is initiated, roller 33 is slightly raised and shifted to the right under the situation being discussed. When blade 36 engages contact 31, further lateral movement of the roller is prevented and, as soon as the highest portion of the lobe has passed the roller, the resiliency of the blade forces the roller downwardly into the trough between the lobe just passed and the next succeeding lobe. In this manner the blade 36 is prevented from vibrating and is precluded from any possibility of engagement with contact 30 for a clockwise rotation of disc 26. Of course, when disc 26 rotates counterclockwise, as viewed in Fig. 4, blade 36 is moved to make and break contact with 30 and is prevented from engagement with contact 31. Thus, the contact 30 or 31 engaged by blade 36 depends upon the direction of rotation of disc 26, and the number of times contact is made depends upon and is directly proportional to the degree of angular rotation of disc 26. This rotation, in turn, is proportional to the angular degree of change in heading of the vehicle. Solenoid 40 or solenoid 41 (depending upon the direction of rotation of disc 26) is thus energized each time a lobe of disc 26 passes beneath roller 33, and each energization of a solenoid moves a corresponding ratchet wheel one step through the action of the spring-retracted pawls 42 and 43. Since the number of lobes on disc 26 and teeth on ratchet wheels 44 and 45 are the same, gear 27 is rotated step-by-step in the same direction and through the same angle as disc 26. Thus, gear 27 is moved by follow-up power means to follow disc 26 substantially synchronously and the component movement of the turret effected through valve gear 18 and the motor controlled thereby, is at all times opposite to, and substantially equal to, the angular change in heading of the vehicle.

Rotation of the scalloped disc 26 in either direction results in applying a series of interrupted electrical power impulses to the corresponding solenoids. The number of impulses corresponds to the angular movement of the disc 26 and the number of scallops of the disc which are successively engaged with the roller 33. As the disc rotates, a scallop carries the roller 33 into contact with the respective contact. After the projection between adjacent scallops passes the roller the latter is released and disengaged from the contact. This interruption of the power supply to the solenoid de-energizes the latter and permits the pawl to be withdrawn from the solenoid under the action of a spring connected thereto. The

pawl is thus positioned to again rotate the ratchet wheel when the solenoid is re-energized as the succeeding scallop in the disc again carries the roller into engagement with the contact.

The resulting rotation of the ratchet wheels effects a corresponding rotation of shaft 34 and bevel gear 27. In this manner the bevel gear 27 of the balancing differential is rotated proportionately to the rotation of the Selsyn receiver or motor 25 and with sufficient power to drive the mechanism of the balancing and combining differentials and the oilgear valve 18.

I claim:

1. In an automatic gun positioning device for tanks of the type having wheels at opposite sides thereof movable in response to the propulsion of the tank, the combination of a differential, flexible cable means connecting the wheels on opposite sides of the tank to respective ones of the input bevels of the differential, the said flexible cable means being operatively connected to the tank wheels to rotate the said differential bevels in opposite direction, a "Selsyn" transmission unit including a transmitter driven from the output of the said differential, the receiver of the "Selsyn" being disposed at the gun turret of the tank, power means controlled by the said receiver, a crown gear associated with the turret turning mechanism, a second differential one of the input bevels of which is driven by the said power means associated with the "Selsyn" receiver, a gear and shaft connection from the said gun turret crown gear to the other differential bevel, a third differential one of the input bevels of which is driven by the output of said second differential, a handwheel connected to the other bevel of said third differential, and a hydraulic pressure system including a valve and a motor, the said hydraulic motor being geared to the said turret crown gear to drive the same and the said hydraulic valve being operatively connected to the output of said third differential, to be controlled thereby.

2. In an automatic gun positioning device for tanks of the type having wheels at opposite sides thereof movable in response to the propulsion of the tank, the combination of a differential, flexible cable means connecting the wheels on opposite sides of the tank to respective ones of the input bevels of the differential, the said flexible cable means being operatively connected to the tank wheels to rotate the said differential bevels in opposite directions, a "Selsyn" transmission unit including a transmitter driven from the output shaft of the said differential, the receiver of the "Selsyn" being disposed at the gun turret of the tank, a crown gear associated with the turret turning mechanism, a second differential, means controlled by said receiver for driving one of the input bevels of said second differential, a gear and shaft connection from the said gun turret crown gear to the other bevel of said second differential, a third differential one of the input bevels of which is driven by the output of the second-mentioned differential, a handwheel connected to the other bevel of said third differential, and a hydraulic pressure system including a valve and a motor, the said hydraulic motor being geared to the said turret gear to drive the same and the said hydraulic valve being operatively connected to the output of said third-mentioned differential, to be controlled thereby.

3. In an automatic gun positioning device for tanks of the type having wheels at opposite sides thereof movable in response to the propulsion of the tank, the combination of a differential, flex-

ible cable means connecting the wheels on opposite sides of the tank to respective ones of the input bevels of the differential, the said flexible cable means being operatively connected to the tank wheels to rotate the said differential bevels in opposite directions, a "Selsyn" transmission unit including a transmitter driven from the output of the said differential, the receiver of the "Selsyn" being disposed at the gun turret of the tank, a gear associated with the turret turning mechanism, a second differential, means controlled by the "Selsyn" receiver for driving one of the input bevels of said second differential, a gear and shaft connection from the said gun turret gear to the other differential bevel, a third differential one of the input bevels of which is driven by the output of said second differential, a handwheel connected to the other bevel of said third differential, and a hydraulic pressure system including a valve and a motor, the said hydraulic motor being geared to the said turret gear to drive the same and the said hydraulic valve being operatively connected to the output of said third differential, to be controlled thereby.

4. In an automatic gun positioning device for tanks of the type having wheels at opposite sides thereof movable in response to the propulsion of the tank, the combination of a differential, flexible cable means connecting the wheels on opposite sides of the tank to respective ones of the input bevels of the differential, the said flexible cable means being operatively connected to the tank wheels to rotate the said differential bevels in opposite directions, a "Selsyn" transmission unit including a transmitter driven from the output of the said differential, the receiver of the "Selsyn" being disposed at the gun turret of the tank, a gear associated with the turret turning mechanism, a second differential, means controlled by said receiver for driving one of the input bevels of said second differential, a connection from the said gun turret gear to the other bevel of said second differential, a third differential one of the input bevels of which is driven by the output of said second differential, a handwheel connected to the other bevel of said third differential, and a hydraulic pressure system including a valve and a motor, the said hydraulic motor being geared to the said turret gear to drive the same and the said hydraulic valve being operatively connected to the output of said third differential, to be controlled thereby.

5. In an automatic gun positioning device for tanks of the type having wheels at opposite sides thereof movable in response to the propulsion of the tank, the combination of a differential, means connecting the wheels on opposite sides of the tank to respective ones of the input bevels of the differential, the said means being operatively connected to the tank wheels to rotate the said differential bevels in opposite directions, a "Selsyn" transmission unit including a transmitter driven from the output of the said differential, the receiver of the "Selsyn" being disposed at the gun turret of the tank, a gear associated with the turret turning mechanism, a second differential, means controlled by said receiver for driving one of the input bevels of said second differential, a connection from the said gun turret gear to the other bevel of said second differential, a third differential one of the input bevels of which is driven by the output of said second differential, a handwheel connected to the other bevel of said third differential, and a hydraulic pressure system including a valve and a motor, the said hydraulic motor being geared to the said turret gear

to drive the same and the said hydraulic valve being operatively connected to the output of said third differential, to be controlled thereby.

6. In an automatic gun positioning device for tanks of the type having wheels at opposite sides thereof movable in response to the propulsion of the tank, the combination of a differential, means connecting the wheels on opposite sides of the tank to respective ones of the input bevels of the differential, the said means being operatively connected to the tank wheels to rotate the said differential bevels in opposite directions, a "Selsyn" transmission unit including a transmitter driven from the output of the said differential, the receiver of the "Selsyn" being disposed at the gun turret of the tank, a gear associated with the turret turning mechanism, a second differential, means controlled by said receiver for driving one of the input bevels of said second differential, a hand wheel connected to the other differential bevel, and means connected to the output of the second said differential for driving the said turret gear.

7. In an automatic gun positioning device for tanks of the type having wheels at opposite sides thereof movable in response to the propulsion of the tank, the combination of a differential, means connecting the wheels on opposite sides of the tank to respective ones of the input bevels of the differential, the said means being operatively connected to the tank wheels to rotate the said differential bevels in opposite directions, a "Selsyn" transmission unit including a transmitter driven from the output of the said differential, the receiver of the "Selsyn" being disposed at the gun turret of the tank, a second differential, means controlled by said receiver for driving one of the input bevels of said second differential, a hand-wheel connected to the other differential bevel, and means connected to the output of the second said differential for driving the said turret.

8. In an automatic gun positioning device for vehicles of the type having wheels at opposite sides thereof movable in response to the propulsion of the vehicle and a gun turnable about a substantially vertical axis, the combination of a differential, means connecting the wheels on opposite sides of the vehicle to respective ones of the input bevels of the differential, a "Selsyn" transmission unit including a transmitter driven from the output of said differential and a receiver, and means controlled by said "Selsyn" receiver for turning the gun.

9. In an automatic gun positioning device for vehicles of the type having wheels on opposite sides thereof angularly movable relative to each other during turning of the vehicle said vehicle also having a gun turnable thereon about a substantially vertical axis, the combination of a "Selsyn" transmitter, means connecting said wheels to the transmitter to actuate the latter in proportion to the relative angular movement between said wheels, a "Selsyn" receiver operatively

connected to said transmitter, and means controlled by said "Selsyn" receiver for turning the gun.

10. In a system for automatically positioning a gun carried for angular adjustment about a substantially vertical axis on and relatively to a vehicle having a pair of wheels relatively rotatable by and in proportion to a change in heading of said vehicle, a transmitter, differential means connecting said wheels and transmitter to actuate the latter proportionally to said relative rotation of said wheels, a receiver, connections actuating said receiver by and in proportion to actuation of said transmitter, power means connected to so adjust said gun, and follow-up means controlled by said receiver for controlling said power means.

11. In an automatic gun positioning system for vehicles of the type having propulsion means at opposite sides thereof and relatively movable when said vehicle changes its heading, said vehicle having thereon a gun trainable about a substantially vertical axis, differential means having a part operated by and proportionally to relative movement between said propulsion means and in a direction corresponding to said change in heading, power means connected to so train said gun, servo-motor means controlling said power means, and telemetric means connected to operate said servo-motor means by and in accordance with the direction of operation of said part.

12. The system as in claim 11, said servo-motor means including reversible electric motor means, and reversing contacts controlled by said telemetric means to control the operation of said motor means by and in correspondence with the direction of operation of said telemetric means.

13. In an automatic gun positioning device for a vehicle having propulsion means at opposite sides thereof, said propulsion means being relatively movable upon a change in heading of said vehicle proportionally to said change of heading, said vehicle having a gun mounted thereon for training about a substantially vertical axis, power means connected to so train said gun, and means responsive to said relative movement of said propulsion means to control said power means to rotate said gun oppositely to the corresponding change in heading of said vehicle.
